UNITED STATES PATENT OFFICE.

JOHN B. PIERCE AND JOSEPH BOND, OF BUFFALO, NEW YORK.

DESIGN FOR THE ORNAMENTATION OF RADIATORS.

SPECIFICATION forming part of Design No. 17,615, dated August 9, 1887.

Application filed July 8, 1887. Serial No. 243,800. Term of patent 14 years.

To all whom it may concern:

Be it known that we, JOHN B. PIERCE and JOSEPH BOND, both citizens of the United States, residing in Buffalo, in the county of Erie and State of New York, have invented and produced a new and original Design for Radiators, of which the following is a specification, reference being had to the accompanying photograph, forming a part thereof.

10. The accompanying photograph represents a perspective view of our newly-designed radiators.

15. 2 is one of the sections or loops. Over the top and upper sides is formed the ornamentation, consisting of figures representing fern-leaves, 3, either with or without the interposed clover-leaves 4. At the base of the section are the representations of fern-leaves 5. The intermediate portion of each section is left 20 plain and the ornâmentations are put on either

in relief or intaglio, the design giving effect as if the radiator were trimmed with ferns.

We claim as our invention—

1. The design for a radiator, consisting of vertical sections or loops connected together 25 and ornamented at their upper and lower portions with figures representing fern-leaves, substantially as shown and described.

2. The design for a radiator, consisting of vertical sections or loops connected together 30 and having ornamental figures at their upper and lower portions, representing fern and interposed clover leaves, substantially as described.

JOHN B. PIERCE.
JOSEPH BOND.
